UNITED STATES PATENT OFFICE.

MELZER G. TURNER, OF WESTBOROUGH, MASSACHUSETTS.

IMPROVEMENT IN SEWING-MACHINES.

Specification forming part of Letters Patent No. **152,260**, dated June 23, 1874; application filed December 3, 1873.

To all whom it may concern:

Be it known that I, MELZER G. TURNER, of Westborough, in the county of Worcester and State of Massachusetts, have invented certain new and useful Improvements in Sewing-Machines, of which the following is a specification:

The nature of my invention consists in combining, with the needle and hook of a straw-sewing machine, of the kind for which a patent was granted to Sidney I. Turner August 24, 1869, No. 94,046, a new loop-holder, said loop-holder consisting of two flat spring-plates moving across the paths of the needle and hook, one plate being at each side of the needle and hook at all times, each plate being provided with a point and an extension, the two points of the plates forming, together, a single point for taking the loop, while the two extensions of the plate form guides for the loop-holding point and insure its action.

Figure 1 is an elevation, showing the needle and hook in connection with my loop-holder. Fig. 2 shows the loop-holder in plan. Fig. 3 shows the loop-holder and needle and hook in elevation, the parts being in the position assumed for casting off the loop by the loop-holder.

B is an ordinary eye-pointed needle; C, a hook-needle; and A the throat-plate—all made and arranged to operate as described in the specification of the patent above referred to. D, Fig. 1, and D D', Fig. 2, show the new loop-holder. This consists of two spring-plates, D and D', each of which is shaped as shown by D, Fig. 1. Each of these plates has a point, the two points E and E' being combined, as shown by E E', Fig. 2, to form the single compound point or loop-holder and cast-off. These plates have extension-pieces F and F', Fig. 2, which serve as guides for the whole looper.

These plates D D', which form the loop-holder, are connected together and arranged to receive a reciprocating motion across the path of the needle and hook.

From the above description it will be seen that the needle E is always between the plates which form the loop-holder, and that the hook C is always between the extensions F F' of the loop-holder, so that the loop-holder is always sure in its action.

The operation of my invention is as follows: The needle B, being threaded, passes up through the stock, dropping back to form the loop, which is caught on the looper, (not shown;) then the needle descends, and the hook C comes up through the stock and takes the loop (which is released from the looper) and carries it down through the stock and below the point E E' of the loop-holder; now, the loop-holder passes forward and catches the loop, as shown at Fig. 3. The hook then passes up between the two plates D D', and leaves the loop upon the points E E', and then retreats to its lowest position, leaving the loop on the points E E'. Now, the loop-holder returns with the stock as it is fed along into such a position that the needle B in its upward stroke passes through the loop which is held on the holder. The continued retreat of the loop-holder casts off the loop and leaves it on the needle B. This completes the operation of forming one stitch.

I claim as my invention—

The combination of the needle B and hook C with the two hooked plates D D', arranged to operate as a loop-holder, substantially as described, and for the purpose set forth.

MELZER G. TURNER.
